R. E. THOMPSON

PILE WIRE

Filed Nov. 1, 1920

Inventor:
Ralph E. Thompson.

by E. D. Chadwick, att'y.

Patented Mar. 4, 1924.

1,485,939

UNITED STATES PATENT OFFICE.

RALPH E. THOMPSON, OF BROOKLINE, MASSACHUSETTS, ASSIGNOR TO GILLETTE SAFETY RAZOR COMPANY, OF BOSTON, MASSACHUSETTS, A CORPORATION OF DELAWARE.

FILE WIRE.

Application filed November 1, 1920. Serial No. 420,962.

To all whom it may concern:

Be it known that I, RALPH E. THOMPSON, a citizen of the United States, residing at Brookline, in the county of Norfolk and State of Massachusetts, have invented certain new and useful Improvements in Pile Wires, of which the following is a specification.

My invention relates to pile wires for use in looms which weave cut-pile fabrics, and is particularly intended to provide a simple and effective arrangement for securing detachable blades in these wires in such manner that the blades will be positively locked to the wires during use but may be readily detached therefrom when desired. It also includes a novel formation of the blade-holding portion of the wire.

The features in which my invention resides are hereinafter described in connection with the accompanying drawing, in which,—

Figure 1 is a side elevation of a portion of a pile wire having my invention applied thereto;

Figure 2 is a top edge view of the same;

Figure 3 is a view similar to Figure 1, showing the pile wire with the blade and blade-locking means removed;

Figure 4 is a transverse section on the line 4—4 in Figure 1; and

Figure 5 is a side view of a detachable blade.

In Figures 1, 2 and 3, 2 indicates the free or front end portion of a pile wire which, except as hereinafter described, may be of any usual or desirable construction, its tip 3 being enlarged vertically and bent laterally at its extremity as is customary. At the rear portion of the tip 3 there is provided a recess 4 for the reception of the detachable blade 5, which is thin and flat and is shown as having a substantially triangular shape, although this particular shape is not essential. The lower edge of the blade is adapted to seat on the bottom of the recess 4, which is just wide enough to receive the blade and is so shaped that when the blade is seated in the recess its cutting edge 6 slants downward and rearward above the rear edge of the tip 3, with its rear end located below the top of the wire 2. 7 indicates a thin strip of spring metal located on one side of the tip 3 and riveted thereto as at 8, its rear end being provided with a small punch pin 9 made of hardened steel and located in transverse

alignment with a perforation 10 extending through the tip 3 in a line which is intersected by the blade 5 when in operative position in the recess 4.

To secure a blade such as 5 to the wire 2 the rear end of the strip 7 is first moved outwardly to an extent sufficient to withdraw the pin 9 from the recess 4 and the blade is then inserted into the recess and positioned therein as shown in Figure 1. The pin 9 is then tapped with a hammer or similar implement and is thereby caused to punch a hole in the blade, which is made thin enough to enable this to be readily done. The result is that the pin 9 is located in the hole punched in the blade, as well as in the perforation 10 on both sides of the blade, which is thereby positively locked to the wire and also prevented from moving longitudinally or vertically in its own plane, and since its lower edge is seated on the bottom of the recess 4 it is also prevented from turning on the pin 9 as a pivot, so that it is immovably held in position for use. To release the blade it is merely necessary to force the strip 7 outward laterally until the pin 9 is withdrawn from the blade, whereupon the latter is free to be lifted out of the slot 4.

Inasmuch as the recess 4 should be located exactly in the longitudinal center of the wire 2 and it is difficult to cut such a recess in the edge of the wire and tip with the required degree of accuracy, I have devised a novel formation of the parts 2 and 3 according to which these parts are made from sheet metal folded along the line of their lower edge, with rivets 11 or other suitable means for holding the folds together in front of and behind the recess 4, half of which is formed in one of the folds by stamping or otherwise and the other half is formed in the other fold. In this way the recess 4 may be formed easily and accurately, but it will be evident that the folded formation is not essential to the operation of the blade-locking means described. When employed, the curved extremity of the tip 3 is preferably provided on one of the folds only, as shown in Figure 2, the other fold being terminated at a short distance ahead of the recess 4. In this way a space is left for the reception of the attached end of the strip 7 without unduly increasing the thickness of the combined

parts, but a tip constructed as above described may obviously be used in connection with various means for maintaining the blades in operative position.

5. I claim:

1. A pile wire provided near its free end with a recess adapted to receive and support a thin blade and with a perforation intersecting said recess, and a spring strip secured to the wire and provided with a punch pin adapted to enter said perforation.
2. The combination of a pile wire provided near its free end with a longitudinally-extending recess and with a transversely-extending perforation intersecting said recess, a thin blade adapted to be inserted into and removed from said recess, and a spring strip secured to the wire and carrying a punch pin located in line with said perforation and adapted to be driven through the blade.
3. The combination of a pile wire provided near its free end with a longitudinally-extending recess and with a transversely-extending perforation intersecting the recess, a thin blade adapted to be inserted into and removed from said recess and to seat on the bottom of the latter in such position that its cutting edge is ex-

posed above the recess and slants downward and backward with respect to the wire, and a spring strip secured to the wire and carrying a punch pin located in line with said perforation and adapted to be driven through the blade after the latter has been seated in the recess, thereby locking the blade to the wire and holding it in fixed relation thereto.

4. A pile wire constructed at its free end of sheet metal folded along the bottom edge of the wire and provided with a blade-receiving recess formed half in one fold and half in the other, said folds being in contact with and secured to each other in front of and behind the recess.

5. A pile wire constructed at its free end of sheet metal folded along the bottom edge of the wire and provided with a blade-receiving recess formed half in one fold and half in the other, said folds being secured together in front of and behind the recess and one of the folds being terminated at a distance behind the extremity of the wire, and blade-locking means secured to the longer fold in front of the shorter fold.

Signed at Boston, Mass., this 29th day of Oct., 1920.

RALPH E. THOMPSON.
